UNITED STATES PATENT OFFICE.

WILLIAM H. PARLIN, OF CANTON, ILLINOIS.

CULTIVATOR.

SPECIFICATION forming part of Letters Patent No. 276,272, dated April 24, 1883.

Application filed September 4, 1882. (No model.)

To all whom it may concern:

Be it known that I, WILLIAM H. PARLIN, residing at Canton, in the county of Fulton and State of Illinois, and a citizen of the United States, have invented a new and useful Improvement in Cultivators, of which the following is a full description, reference being had to the accompanying drawings, in which—

Figure 1 is a rear elevation, the plow-beams being shown in section. Fig. 2 is a side elevation, one wheel being removed. Fig. 3 is a detail, being a plan of one plow-beam and a device connected therewith, by means of which, when desired, the plows can be supported free from the ground. Figs. 4 and 5 are details, Fig. 5 being a section at line *x* of Fig. 4. Fig. 6 is a plan of the parts represented. Figs. 7 and 8 show a modification.

It is common to connect the two gangs of plows in a cultivator with each other by means of an arched bar, and to hinge the wheels to the ends of such bar. Heretofore it has been usually thought important to so construct cultivators that the wheels would be kept in the line of progression when one beam was advanced a little forward of the other or when the plow-beams were moved laterally. I think it desirable to have a cultivator so constructed that when either gang of plows is moved laterally the wheel will also be moved out of the line of progression, either to the right or to the left.

My invention relates, first, to devices by means of which the wheels are hinged to the arched bar; second, to devices by means of which, when the operator moves either plow-beam laterally, the corresponding wheel will also be moved a little out of the line of progression, either to the right or left, as the case may be.

In the drawings, *A* represents an arched bar having upon each side a horizontal portion, *a*, to which the plow-beams are connected, and at each end a downward extension, *b*.

B is a bracket having ears *c* at the top and bottom, through which ears the end *b* of the arch passes, thus hinging the bracket upon the end of the arch. *d* is a spindle upon which the wheel is supported. It is firmly secured to the bracket *B*. In manufacturing the spindle and bracket may be cast together. From

the upper ear, *c*, of the bracket *B* there is a forward extension or bar, *e*.

C is a draft-bar hinged upon the end *b* of the arch.

D is a sleeve upon the end *b* of the arch, between the ear *c* and the socket of the draft-bar *C*. Of course the draft-bar *C* and the sleeve *D* may be cast together.

E is a bar pivotally connected at its forward end, *f*, with the draft-bar *C*, or, as shown, to a little projection upon such draft-bar. At the center of this bar *E* is a short slot, *g*, through which passes a bolt, *h*, the lower end of which is secured in the forward end of the extension *e*, the ear *c* being held loosely at this point in connection with the forward end of the extension *e*, so that such bar *E* can turn upon the bolt *h*.

F is a small bent rod, one end of which is rigidly secured, as shown, to one end of a small plate, *i*, while the other end of this plate is pivotally connected with the rear end of the bar *E*. The plate *i* may be omitted, one end of the rod *F* being pivotally connected directly with the rear end of the plate *E*. The other end of this rod *F* passes through a loop or eye, *j*, upon the side of the plow-beam.

G *G'* are the plow-beams, hinged in a suitable manner upon the horizontal part *a* of the arched bar *A*, so that the plow-beams can have either a vertical or lateral movement.

The operation of this part of my invention is as follows: The machine is designed to cultivate both sides of a row of plants at the same time, and to be drawn by two animals, one of which is hitched to each of the draft-bars *C*. The wheels, being pivoted upon the lower ends of the arch, are each free to be turned out of the direct line of progression, and if the operator moves the rear end of the plow-beam *G* toward its wheel that part of the wheel which is forward of the spindle will be turned outward and out the line of progression, because the rear end of the bar *e* will by the action of the bent rod *F* be thrown a little toward the wheel, and this movement of this bar *E* will move the forward end of the extension *e* a little toward the wheel, because the bar *E* is pivoted at its forward end to the draft-bar *C* and near its center to the extension *e*, and as this extension *e* is connected with the bracket *B* its

movement either to the right or left causes the bracket to spring or turn upon the part *b* of the arch, and the wheel-spindle being permanently connected with the bracket *B*, the wheel must also be turned by the movement of the bracket *B*. If this beam *G* be moved in the opposite direction, away from the wheel, the forward part of the wheel will in the same manner be thrown inward a little and out of the line of progression. The operation as to the other beam is precisely the same as that already described. If the two plow-beams were connected together at their rear ends, then when they were moved laterally both wheels would be thrown out of the line of progression at the same time, one being thrown outward and the other one inward. The draft of the animals maintains the draft-bar *C* in the line of progression. This construction, which causes the wheels to be moved out of the line of progression when the plow-beams are moved laterally, is desirable, because the operator has more perfect control of the cultivator, and, in dodging plants, is aided by the action of the wheels. It frequently happens in use that the cultivator gets out of line, the center of the machine being carried to one side of the center line, especially on side hills or where one of the horses is inclined to crowd. Then the operator, by turning the wheels a little, can quickly bring the cultivator to the proper place. This construction can be used with cultivators which have a tongue; but it is more desirable with the tongueless cultivator. With this construction the wheels are controlled by the operator and not by the animals.

In Figs. 7 and 8 I have shown a modification of this feature, by which I dispense with the bar *E* and make a direct connection between the plow-beam and the extension *e* by means of an angular rod having two arms, *l* and *m*, the rear end of *l* passing through an eye, *n*, upon the plow-beam, and the end of the arm *m* passing down into a hole in the extension *e*. The other end of *m* is extended beyond the point of connection with *l*, and passes loosely through a hole in a brace or support, *o*, which is connected with the arched bar *A* at one end and with the draft-bar *C* at the other end. Some other support for this end of the rod *m* might be used. *p* is simply a brace connecting *l* and *m*. With this construction, if the rear end of the plow-beam be moved either to the right or to the left, the extension *e* from the bracket *B* will also be moved either to the right or to the left, carrying with it the wheel, as before, the rod *m* sliding in its support *o*. Thus the operation with this modification is precisely the same as before, the difference in construction being that the connection between the plow-beam and the extension *e* is made in a somewhat different manner than before described.

H is a bar hinged near its forward end to one side of one of the plow-beams. Near the

forward end of this bar *H* is a lateral projection or flange, *k*, which, as shown in Fig. 3, extends over the beam. This projection *k* is notched at its forward end, and the lip *k'* is curved downward slightly. The outer end, *r*, of the bar *H* is enlarged and bent.

The operation of this part of my invention is as follows: When the bar *H* is not in use it can be supported by the side of the plow-beam by means of the flange *k*, which rests upon the beam, and the lip *k'* will prevent the flange *k* from slipping off from the beam. By lifting up the rear end of the bar *H* the lip will be carried up above the beam, and then the bar *H* can be moved over a little away from the beam, and then can be brought down to the ground, and at the same time, if the beam be lifted a little, it can be made to enter the notch at the forward end of the flange *k*, and thus, the bar *H* being of suitable length, the plows will be supported free from the ground, the outer or lower end, *r*, of the bar *H* resting on the ground. The position of this bar and of the plow-beam, when the plows are out of the ground, is shown by dotted lines in Fig. 2.

I have shown and described the part *e* as an extension from the bracket *B* and integral therewith. This part might be a separate arm or bar secured to the bracket; but the first form is the best.

Instead of placing the notched flange or plate *k* upon the bar *H*, a notched flange or plate might be secured to and project from the plow-beam, such notched flange being arranged so as to receive and hold the bar *H* by the side of the beam, and also so arranged that the notch will engage with the bar *H* when the bar is down for the purpose of supporting the beam in an elevated position.

I am aware that it is not new to swivel the wheel-support of a cultivator and connect such support with the plow-beam in such manner that lateral movements of the beam impart corresponding movements to the wheel; but such is not broadly claimed by me.

What I claim as new, and desire to secure by Letters Patent, is as follows:

1. In a cultivator, the combination, with an arch or frame, *A*, having a horizontal portion, *a*, and vertical portion *b*, and a plow-beam, *G*, pivotally connected with the portion *a* to move laterally, of the wheel-carrying bracket *B*, pivoted to the said vertical portion *b*, and provided at its upper end with a forward extension, *e*, and a connection between the forward extension and the plow-beam, whereby lateral movements of the latter will swing the bracket on the vertical portion of the arch or frame, substantially as described.

2. In a cultivator, the combination of an arch or frame having the vertical portion *b*, and a plow-beam pivotally connected with the arch or frame to move laterally, with the wheel-carrying bracket *B*, having top and bottom ears, *c*, pivoted on the said vertical portion *b*, the upper ear having a forward extension, *e*, and the

connecting devices between the forward extension and the plow-beam, whereby lateral movements of the latter will swing the wheel-carrying bracket on the vertical portion of the arch or frame, substantially as and for the purposes described.

3. In a cultivator, the combination, with the arch or frame A, the plow-beam G, pivotally connected therewith to permit its lateral movement, and the pivoted wheel-carrying bracket B, provided with the forward extension, e, of the bar E, pivoted at its forward portion, and connected at or near the center of its length with the forward extension, and the rod F, connecting the rear end of the said bar with the plow-beam, substantially as and for the purpose described.

4. In a cultivator, the combination of an arched bar, A, bracket B, hinged to the end b of the arched bar and provided with a wheel-spindle, an extension or arm, e, connected with the bracket B, the pivoted bar E, having a slot, g, connected with the arm or extension e, and a connecting device between the rear end of the slotted bar and the plow-beam, whereby when a lateral movement is given to the plow-beam the wheel will be thrown out of the line of progression, substantially as specified.
